(57) **CLAIM**

The ornamental design for a tire, as shown and described.

DESCRIPTION

FIG. 1 is a front elevational view of a tire showing my new design;

FIG. 2 is a left side view thereof;

FIG. 3 is a first perspective view thereof;

FIG. 4 is a second perspective view thereof;

FIG. 5 is an enlarged view of portion 5 of FIG. 1;

FIG. 6 is an enlarged view of portion 6 of FIG. 2;

FIG. 7 is an enlarged view of portion 7 of FIG. 3;

FIG. 8 is an enlarged view of portion 8 of FIG. 3;

FIG. 9 is an enlarged view of portion 9 of FIG. 3;

FIG. 10 is an enlarged view of portion 10 of FIG. 4;

FIG. 11 is an enlarged view of portion 11 of FIG. 4; and,

FIG. 12 is an enlarged view of portion 12 of FIG. 4.

In the drawings, the broken lines depict environmental subject matter only and form no part of the claimed design.
